UNITED STATES PATENT OFFICE.

ERNEST SYDNEY, OF LONDON, ENGLAND, ASSIGNOR TO JAMES ROBINSON & SONS (ROMILEY), LIMITED, OF ROMILEY, ENGLAND.

MEANS APPLICABLE FOR USE IN THE STEAMING OF HATS.

Application filed August 13, 1928, Serial No. 299,193, and in Great Britain April 16, 1928.

This invention has reference to the manufacture of hats composed of felt and relates to an improved method of and apparatus applicable for use more particularly in the 5 steaming operation connected with the manufacture of soft felt hats; the object being to enable the said operation to be performed in an approximately continuous manner on the hat forms as they are successively submitted to the action of the steam, thereby 10 effecting an economy in time and labour.

In steaming hat forms according to the usual practice it is necessary in order to expedite the progress of the operation with the 15 existing machines to extract the steamed form from the mould or clamp before it has become sufficiently cooled to admit of safe removal. Thus, there is always the risk of 20 damaging the steamed form while considerable loss of time is entailed if it be allowed to remain in the mould for the whole of the cooling period.

According to this invention, the steaming is carried out continuously and successively 25 by inserting the hat forms into rotatably mounted moulds or clamps and, after subjecting the said forms to the action of the steam, turning the moulds or clamps through an angle into a vertical attitude and rotating 30 the same to bring successive moulds or clamps into operative position.

Apparatus adapted for carrying out the method of working above described comprises a number or series of mould plates or 35 clamps mounted on radial arms extending from a rotatable carrier or turn-table which is mounted on a pillar or other support carried by a suitable base or bed plate. The rotatable carrier may be mounted on ball or 40 other antifriction bearings and the moulds or clamps, each of which comprises an upper and a lower plate, are respectively hinged or attached to the said carrier in such a manner that, while the whole mould structure is 45 capable of being turned through a right-angle, the upper plate may be similarly turned independently of the lower plate. The latter when in a horizontal position is adapted to 50 close or seal the upper end of a chamber conveniently mounted on the base or bed plate; steam being admitted to the said chamber by way of a pipe or pipes which may be led through the pillar or support and from the latter to the lower end of the steam chamber, there being a regulating cock convenient

to the said chamber and a shut-off valve on the supply pipe exterior to the machine.

The several moulds or clamps are preferably provided with weights or equivalent contrivances to retain them in the turned or 60 vertical position.

In order that the invention may be readily understood and carried into effect, same will now be more fully described with reference to the accompanying drawings, in which:— 65

Figure 1 is a side view of the apparatus partly in section.

Figure 2 is a corresponding plan.

Figure 3 is a view in elevation looking at the front or right-hand side of Figure 1. 70

Figure 4 is a detail view of a form of hinge connection between the arms pertaining to the rotatable carrier and the mould plates or clamps.

a a indicate mould plates or clamps which 75 are mounted on arms *b b* extending radially from the rotatable carrier or turn-table *c*. The latter is mounted on ball or other antifriction bearings such as indicated at *d* on the upper end of a pillar *e* or other support 80 carried by a base or bed plate *f*. The lower plate of each mould or clamp has a radially extending arm *g* which is hinged at *h* to the arms *b b* extending from the turn-table *c* and the upper plate of each mould is hinged at *i* 85 to posts *k k* on the outer ends of the arms *b b*; the hinge fitting to the upper plate carrying arms *l l* to which weights *l¹ l¹* are attached. Similarly, the arms *g* have weights 90 *g¹* attached thereto.

m indicates a chamber to which steam is supplied by way of a pipe *m¹* which passes through the pillar *e* and is provided, exterior to the apparatus, with a shut-off valve *m¹¹*, the supply pipe, at or near its connection with 95 the chamber, being provided with a regulating valve, indicated at *m¹¹¹*. The said chamber preferably contains a layer of material such as straw indicated at *n*, which is packed between perforated metal discs or 100 plates *n¹ n¹*. The chamber *m* is suitably mounted on the base or bed plate *f*.

o indicates the screw device for clamping the parts of the mould together when the material of the hat has been placed therein and 105 *p* indicates the device for imparting pressure to the hat block. The use and purpose of these devices will be readily understood by those acquainted with the art.

q q are bracket arms, shown mounted on 110

the wall of the steam chamber m , for enabling the mould or clamps a to be centred in relation to the said chamber.

Each mould a may be provided with a handle or grip (not shown) for use in effecting the rotative movement about the centre of the pillar or support.

In the apparatus illustrated, the rotatable carrier or turn-table c is adapted to accommodate four moulds or clamps a . This number may, however, be varied by increasing or otherwise modifying the same as circumstances may require or according to desire.

In using the apparatus, a mould having been brought into position over the steam chamber and the upper plate turned up about the hinge i , a hat r indicated in dotted lines in Figure 1, is inserted, whereupon the said upper plate is turned down into position on the lower plate and clamped thereto by means of the screw device o . Pressure is then applied to the hat block by manipulating the screw device p and steam admitted to the chamber m by opening the valve m^1 pertaining to the supply pipe m^1 the volume and pressure being adjusted by means of a regulating device m^{11} . Upon the completion of the steaming operation, the steam supply is shut off and the mould raised by turning the same about the hinge joint h into the vertical position as shown clearly in Figures 1 and 3 in which it will be retained by the counter balance weights g^1 and b^1 . The carrier c is then given a partial rotation which brings another mould a into position and centered over the steam chamber and the several steps hereinbefore described repeated and so on with each mould in succession.

It is found in working with a machine adapted to accommodate four moulds that upon the completion of the steaming operation in connection with the fourth mould the hat form treated in the first mould of the series will be sufficiently cooled to ensure a perfect and lasting shape and to allow the hat to be removed without fear of shrinkage or any loss of time; both of which are unavoidable under all other methods of steaming. Thus the apparatus admits of continuous and successive working each hat being in full view of operator throughout the process. The improved method of working results in the production of hat forms devoid of the inconsistencies incidental or often attributed to the method of working heretofore practised and enables a great saving in time and labour to be effected.

I claim:—

1. In apparatus for steaming hat forms, the combination with a chamber and means for supplying steam thereto of a series of moulds

each comprising separable plates and adapted to receive and clamp the hat forms, a rotatably mounted carrier, radial arms extending from the said carrier, hinged connections between the separable plates and between the respective plates and the arms, the arrangement being such that the upper plate or the whole mould structure may be turned into a vertical attitude and when the hat form is inserted and the upper plate closed thereon and on the lower plate and the whole mould structure is in a horizontal position over the steam chamber so as to close the same the hat form is steamed by the action thereon of the steam supplied to the said chamber.

2. In apparatus for steaming hat forms, the combination with a chamber and means for supplying steam thereto, of a series of moulds comprising separable counterweighted plates and adapted to receive and clamp the hat forms, a rotatably mounted carrier, radial arms extending from the said carrier, hinged connections between the said separable plates and between the respective plates and the arms, the arrangement being such that the upper plate or the whole mould structure may be turned into a vertical attitude or turned so as to close the steam chamber for the steaming of the hat form.

3. In apparatus for steaming hat forms, the combination with a chamber and means for supplying steam thereto, of a series of moulds comprising a hat block and separable counterweighted plates adapted to receive and clamp the hat forms, a rotatably mounted carrier, radial arms extending from the said carrier, hinged connections, between the separable plates and between the respective plates and the arms and screw operating means for clamping the plates of the mould and imparting pressure to the hat block.

4. In apparatus for steaming hat forms, the combination with a chamber and means for supplying steam thereto, of a series of moulds comprising a hat block and separable counterweighted plates adapted to receive and clamp the hat forms, a rotatably mounted carrier, a pillar and antifriction bearings thereon for supporting the carrier, radial arms extending from the said carrier, hinged connections between the separable plates and between the respective plates and the arms and devices pertaining to the mould structure operable by means of screws for effecting the clamping of the hat forms and imparting pressure to the hat block.

In testimony whereof I have hereunto subscribed my signature this 24th day of July, 1928.

ERNEST SYDNEY.
